(57) **CLAIM**

The ornamental design for the tweezer, as shown and described.

DESCRIPTION

FIG. 1 is a perspective view of the tweezer showing our new design, the configuration of the tip not being a part thereof;

FIG. 2 is one side view thereof;

FIG. 3 is the other side view thereof;

FIG. 4 is a top view thereof;

FIG. 5 is a bottom view thereof;

FIG. 6 is a rear view thereof; and,

FIG. 7 is a front view thereof.

The broken lines, immediately adjacent the solid line disclosure, represent the bounds of the claim and all other broken lines are for illustrative purposes only. None of the broken lines form a part of the claimed design.
